UNITED STATES PATENT OFFICE.

ALFRED HUBERT ROY FEDDEN AND LEONARD FREDERICK GEORGE BUTLER, OF
BRISTOL, ENGLAND, ASSIGNORS TO THE BRISTOL AEROPLANE COMPANY LIMITED,
OF BRISTOL, GLOUCESTER COUNTY, ENGLAND.

CYLINDER FOR INTERNAL-COMBUSTION ENGINES.

1,398,849.

Specification of Letters Patent. Patented Nov. 29, 1921.

Application filed November 1, 1920. Serial No. 421,134.

To all whom it may concern:

Be it known that we, ALFRED HUBERT ROY FEDDEN and LEONARD FREDERICK GEORGE BUTLER, both subjects of the King of England, and both residing at Bristol, England, have invented certain new and useful Improvements in Cylinders for Internal-Combustion Engines, of which the following is a specification.

10 This invention is for improvements in or relating to cylinders for internal combustion engines, and has for its object to provide a construction which is particularly suited for small and light air-cooled engines such as are 15 used on light motor vehicles. It will be understood, however, that the invention is not restricted to such engines.

According to this invention a cylinder head for an internal combustion engine comprises a cylindrical portion adapted to inclose the open end of the cylinders spigoted in it, and to be secured thereto, and an end wall formed with hoods to constitute the inlet and exhaust passages and reinforced by 25 external webs normal to the outer surface of the wall and extending across it. These external webs are utilized as cooling fins.

Preferably the cylindrical portion above mentioned is also formed with cooling fins 30 extending around it in planes transverse to the longitudinal axis of this cylinder. Preferably also the fins on the end wall of the cylinder head are arranged at right angles to the side walls of the hoods above mentioned, 35 so that this end-wall is stiffened in two directions at right angles to one another.

According to another feature of the invention the valve seats are carried by the cylinder head preferably being cast in and 40 the valve-operating levers are mounted in brackets or lugs which may be also formed integrally with or secured on the cylinder head.

In the accompanying drawings which 45 illustrate a specific embodiment of this invention,

Figure 1 is a vertical section of the cylinder head on line 1—1 of Fig. 2;

Fig. 2 is a central longitudinal section of 50 the cylinder;

Fig. 3 is a side elevation of the head, look-

ing in the direction of the arrow 3 in Fig. 1; Fig. 4 is a plan of Fig. 3;

Fig. 5 is an end view of the cylinder looking on the bottom of Fig. 2; 55

Fig. 6 is a plan of the cylinder looking on the top in Fig. 2; and

Fig. 7 is a view looking on the bottom of the cylinder head of Fig. 1.

Like reference characters indicate like 60 parts throughout the drawings.

Referring first to Fig. 1, the cylinder head is preferably an aluminium casting, having a cylindrical portion 10, and a flat end-wall 11. This head is preferably machined all 65 over inside and at the open end of the cylindrical part is provided with a machined recess 12 which fits over the end of the cylinder. The cylindrical portion 10 is provided with cooling-fins 13, extending laterally from 70 it transverse to its axis. The end wall 11 has cast integrally with it on its outer or upper side, hoods or pipe-like portions 14, 15 serving as the inlet and exhaust passages respectively. These hoods are disposed symmetrically on the valve head, so that their center-lines lie on the same diameter of the head, and the open ends 16, 17 face in opposite directions away from one another along this diameter. The end faces of the hoods as 75 shown, for example, in Fig. 3, are shaped in any desired manner for the attachment of the inlet and exhaust conduits thereto.

In addition to the cooling-fins 13 on the head, there are also provided fins 18 extending transversely across the head at right-angles to the diameter whereon the two hoods aforesaid are situated. These fins are normal to and upstanding from the surface of the head. It will be seen that the hoods 14, 15 being cast integrally with the flat end-wall 11, stiffen it against bending about a line normal to the diameter on which the two hoods are situated; similarly, the cooling fins 18 which lie at right-angles to the hoods, and 90 their side walls, stiffen the end-wall 11 against bending about the diameter on which the hoods lie, or a line parallel thereto. The whole head is therefore adequately reinforced. 95

Suitable bosses are formed on the head to receive bolts whereby the head is secured to 100

the cylinder body. The pair of bosses 19, 20 extend through and are integral with the fins 13, and terminate at the uppermost of these fins, the belt holes in these bosses being indicated at 21, 22, in Fig. 3. The other bosses are conveniently situated beside the hoods, and are formed integrally with the side walls thereof. Thus the bosses 23, 24 lie one on each side of the inlet hood 14, and the bosses 25, 26 are similarly formed integrally with the exhaust hood. It is convenient when the bosses are thus formed integrally with the hoods that they should be of a greater depth, in order that the nuts when seated on the bosses may be accessible. This greater depth is most clearly shown in Fig. 3.

Provision is made for the sparking plug of the cylinder by an aperture 27, bored and tapped to receive the plug, and this aperture is so situated as to bring the plug close to the inlet port on the cylinder.

The inner ends of the two hoods 14, 15 constitute the inlet and exhaust ports respectively for the cylinder, as shown at 28, 29, in Figs. 1 and 7. The valve seats, are constituted by rings 30, 31, which are cast in position on the head, being provided with flanges 32, 33 respectively, which are notched, and formed in any convenient manner to interlock with the casting. The flanges aforesaid are cut away at the parts 34, 35 for the valve seats which are closest to one another, that is to say, at the middle of the cylinder, so as to provide for an adequate thickness of metal at the part 36 of the end-wall 11 between the two valve ports. In this way, the maximum diameter of the inlet and exhaust port openings can be used without weakening the head.

The valve stems extend upward through suitably positioned openings 37, 38 in the upper wall of the hoods 14, 15 respectively, and are operated by any desired type of over-head valve mechanism. Where valve-operating levers are used, they are mounted in brackets 39, 40, 41 (see Fig. 4) these brackets being constituted by certain of the cooling fins 18 being extended upward as shown in Fig. 3. To insure that these brackets are of adequate strength, the three fins which are used are made somewhat thicker than the other fins, and they are connected together near their upper end by a bridge-piece 42, as shown in Fig. 3. The upper ends of the brackets are thickened up, as will be seen in Fig. 4, and bored to receive a spindle which carries the operating levers for the inlet and exhaust valves respectively.

The cylinder with which the head hereinbefore described is used, is illustrated in Figs. 2, 5 and 6. In the case of an engine for a light motor vehicle, the cylinder 43 is conveniently made of cast iron, and is open at both ends. At its upper end it is machined, as at 44, to fit closely within the recessed

portion 12 of the cylinder head, and it is secured thereto by bolts passing through the bosses aforesaid on the cylinder head and through suitably spaced holes 45 which are provided in bosses 46 around the cylinder. The cylinder 43 is provided with radially extending cooling-fins 47, similar to the fins 13 on the head aforesaid, and the bosses 46 are conveniently formed by a thickening up of the first two fins of the cylinder. 75

Near its lower end the cylinder is provided with an external flange 48, having bolt holes 49, or other convenient means whereby it may be secured to a crank case, and preferably the outside of the cylinder is machined at its lower end 50 so that it spigots into the crank case. 80

Referring to Fig. 5, it will be seen that the cooling fins 47 are recessed at 51 to permit the insertion of bolts in the holes 49 aforesaid. 85

It may be observed in regard to the spigotting of the cylinder-barrel in the head that it is essential that the male portion of the spigot should be of a fair depth to prevent the explosion flame from destroying the joint between the barrel and head. It is possible to use the cylinder of the construction illustrated without any gasket between the barrel and head, but with cylinders of a larger size 90 where a gasket might be necessary it is essential that it should be effectively shielded from contact with the flame and this shielding is provided by the depth of the spigot. 95

As regards the attachment of the head to the cylinder barrel, the preferred method is to use bolts as hereinbefore-described, but in some cases, such for example as with large sizes, it is necessary to use studs, and these are secured in the cylinder-head. This necessitates increasing the clearance between the bosses 46 on the cylinder-barrel and the next lower cooling-fin so as to permit the insertion of the nuts, but otherwise the general arrangement is the same. 100 105 110

When cast cylinder-barrels are used, the bosses are cast in position as shown in Fig. 6, but for steel cylinders it is preferred to provide the necessary metal for the bosses all around the cylinder and to machine it 115 away between the bosses to form the cooling-fins.

What we claim as our invention and desire to secure by Letters Patent is:

1. A working cylinder for internal combustion engine comprising in combination a cylinder head, an open-ended cylinder spigoted therein, cooling fins upon said head extending radially in planes transverse to the longitudinal axis of the cylinder, the aforesaid head formed with oppositely directed hoods of the cylinder, which hoods constitute the inlet and exhaust passages, external cooling fins extending normally from the outer surface of the end wall parallel with 120 125 130

one another and substantially at right angles to the upstanding side walls, and brackets to support the valve operating mechanism, which brackets are constituted by extensions 5 of the cooling fins on the end wall of the cylinder head.

2. A working cylinder for an internal combustion engine, comprising in combination a cylinder-head, an open-ended cylinder spigoted therein, cooling fins upon said head extending radially in planes transverse to the longitudinal axis of the cylinder, the aforesaid head formed with two hoods on the same diameter of the cylinder, which 10 hoods constitute the inlet and exhaust passages, external cooling fins extending nor- 15

mally from the outer surface of the end wall parallel with one another and at right angles to the line whereon the said hoods are situated, and brackets to support the valve-operating mechanism, which brackets are constituted by extensions of the cooling fins on the end wall of the cylinder head. 20

In testimony whereof we have signed our names to this specification in the presence of 25 two subscribing witnesses.

ALFRED HUBERT ROY FEDDEN.

LEONARD FREDERICK GEORGE BUTLER.
